UNITED STATES PATENT OFFICE.

CROMWELL P. WEAVER, OF PHILADELPHIA, PENNSYLVANIA, ASSIGNOR OF
ONE-HALF TO JOHN L. CARRE, OF SAME PLACE.

GATE-LATCH.

SPECIFICATION forming part of Letters Patent No. 349,469, dated September 21, 1886.

Application filed August 18, 1886. Serial No. 211,188. (No model.)

To all whom it may concern:

Be it known that I, CROMWELL P. WEAVER, of Philadelphia, in the county of Philadelphia and State of Pennsylvania, have invented a new and valuable Improvement in Gate-Latches; and I do hereby declare that the following is a full, clear, and exact description of the construction and operation of the same, reference being had to the annexed drawing, making a part of this specification, and to the letters and figures of reference marked thereon.

My invention has relation to pivoted latches for doors, gates, or other like fixtures; and it has for its object to provide a simple, durable, and effective latch which is readily manipulated, and which is provided with a pivoted dog for locking it in position to fasten the gate or door, thereby preventing accidental unfastening.

20 My invention accordingly consists of a pivoted latch of right-angle form, having a guide or stop for one arm thereof, which arm is provided with a handle or stud and a pivoted dog for engaging with the other arm, the latter arm having a pin or stud thereon to lock the latch in its fastening position.

Referring to the accompanying drawing, which is a perspective of a part of a door or gate and post, and of a latch embodying my improvements, A represents the door or gate; B, the post or jamb, having keeper b; and C the latch, which consists of a right-angle or bell-crank lever having arms c c', and is suit-

ably pivoted at c² to a plate or bar, c³, suitably secured to the door or gate A. The arm 35 c has a handle or stud, c⁴, by means of which the latch is preferably manipulated, and the arm c' has a stud or pin, c⁵, which forms a stop-pin for a pivoted dog, D, the end d of which is adapted to slide over in front of the 40 latch-arm c', and abut against pin c⁵, to hold or lock the latch in position for fastening the gate or door, as shown in the drawing. To unfasten the latch, the dog D is first thrown over in the direction indicated by arrow x. 45

To limit the movement of the latch or its arm c, a suitable guide, E, is provided, which is fastened to the door or gate A in any desired manner.

What I claim is—

1. The right-angle latch C, having on its arm c' a stud or pin c⁵, in combination with a pivoted dog, D, adapted to engage arm c' and stud c⁵, substantially as and for the purpose set forth. 50

2. The right-angle latch C, having on its arm c' a stud or pin, c⁵, in combination with pivoted dog D and guide E, substantially as set forth. 55

In testimony that I claim the above I have hereunto subscribed my name in the presence of two witnesses.

CROMWELL P. WEAVER.

Witnesses:

ALLEN H. GANGEWER,

JOS. J. KNOX.
